U.S. Cl. D80—9

FIGURE 1 is a perspective view of a rotary rack embodying our new design;

FIGURE 2 is a top plan view of one of the shelf units;

FIGURE 3 is a side elevational view of FIGURE 2;

FIGURE 4 is a bottom plan view of FIGURE 2; and

FIGURE 5 is a fragmentary cross sectional view taken on line 5—5 of FIGURE 3.

The dominant features of our design reside in the specific configuration of the shelf units forming the rack.

We claim:

The ornamental design for a rotary rack, as shown and described.
